Patented Oct. 11, 1910.

UNITED STATES PATENT OFFICE.

CHARLES A. WOODRUFF AND GEORGE E. McELROY, OF NEWARK, NEW JERSEY.

SIGN-HOLDER.

972,312.

Specification of Letters Patent. Patented Oct. 11, 1910.

Application filed January 18, 1910. Serial No. 538,760.

To all whom it may concern:

Be it known that we, CHARLES A. WOODRUFF and GEORGE E. McELROY, of the city of Newark, county of Essex, and State of

5 New Jersey, have invented a new and useful Improvement in Sign-Holders, of which the following is a full, clear, and exact description.

Our invention relates to improvements in 10 devices for holding display signs or cards and more particularly for holding such signs or cards as are used in connection with automobiles or other vehicles, and particularly the license tags or cards of such vehicles.

It is desirable to hold the display or 15 license cards or signs of automobiles in such a way that they will be prominently displayed; it is also desirable and in some 20 States a legal requirement, that the tags or cards be held well above the ground so that they will not be obscured by dust; and it is also necessary to provide a convenient and quick means for securing the card in place 25 so that in passing from one State to another, the card or sign can be easily removed and another one substituted for it. Usually the methods for attaching these signs, tags, or cards, is crude, and the attachment is made 30 with considerable difficulty.

The object of our invention is to produce 35 a very simple and yet secure holding device which can be clamped to the spring or other convenient part of the vehicle, such as an automobile, to provide means for instantly inserting and firmly securing the sign in the holding device, further to provide an adjusting arrangement by which the sign can be easily placed in a vertical position 40 so as to be prominently displayed without regard to the position or pitch of its support, and finally to arrange the holding device so that it can be easily swiveled or turned laterally in order that a clear space 45 may be left in case one wishes to crank the machine.

Another object of our invention is to secure the above results in a very simple, positive and inexpensive way so that the holder 50 will not be an expensive luxury.

With these ends in view and with the general object of producing a satisfactory sign holder which can be easily attached to a vehicle and which will properly display the 55 sign or card, our invention consists of a sign holder adapted to yieldingly but securely

hold the card and means for attachment to a vehicle, the details of which will be hereinafter described and the novel features claimed.

Reference is to be had to the accompanying drawings forming a part of this specification, in which similar reference characters indicate corresponding parts in all the views.

Figure 1 is an edge view of the device as applied to the front part of the automobile. Fig. 2 is a broken enlarged front view showing a sign displayed in the holder. Fig. 3 is a plan view of the holding device, and Fig. 4 is a detail of the clamp by which the holding device is secured.

The holder is provided with opposed vertical flanged jaws or members 10 and 10^a one below the other, these being movable in relation to each other, and as shown the lower one is normally stationary while the upper one moves. The lower jaw may, however, be turned on the post 12, as hereinafter described. The jaws are preferably grooved transversely as shown clearly in Fig. 1 so that the sign which is in the form usually of a metal sheet or card, can be easily slipped into the grooves, thus being held securely by the walls of the grooves against displacement forward or back, while the pressure of the jaws toward each other will prevent the sign from slipping lengthwise. As a convenient way of mounting the jaws, they can be provided with a vertical post 12, which is fixed to a support and on which the jaws slide, the upper jaw being normally pressed downward by a spring 13 which coils around the upper end of the post between the upper jaw and an abutment which can conveniently be a nut as 95 14. Thus the sign 11 is held firmly by the pressure of the spring 13 and when it is to be removed or inserted, the jaw 10^a can be readily grasped and forced up against the spring 13, thus relieving the pressure and permitting the ready movement of the sign.

The holding device is provided with a rearwardly extending shank 15 which is fast to the post 12, and while this shank may be rigid, it is preferably jointed as shown at 17 so that an extension 15^a beyond the joint connects with the clamp 19 to be presently referred to, while the joint may be tightened and the parts 15 and 15^a made rigid by means of a suitable thumb bolt 18. The object of the joint in the shank is to provide for tipping the sign-holder back.

ward or forward so as to bring it into a proper vertical position. Thus it is not material as to what position the clamp 19 assumes because the adjustable shank permits the holder to be regulated with relation to its clamp or support.

So far as this invention is concerned, the form of the shank or of its supporting clamp is not very material, although we claim the form shown. As illustrated, the member 15^a of the shank terminates in a clamping piece 20, which abuts with a corresponding member 20^a, and each member has vertical parts 21 and overlapping flanges 22, so that the opposed members may be conveniently made to grasp the spring of the vehicle or some other convenient part. After the parts 20 and 20^a are placed upon the spring or other support, they can be tightened by means of the screw 26 which extends through the boss 25 on the member 20^a, and is threaded into the boss 24 on the member 21.

From the foregoing description it will be seen first, that the clamp can be very readily applied to the spring of a vehicle or to some part beneath the body, that the holder can be readily adjusted so as to assume a vertical position and can be fastened by means of the bolt 18, and that by lifting the upper jaw 10^a the sign 11 can readily be placed in position or removed.

Where the device is arranged on the front part of a vehicle, it is sometimes desirable to turn the sign laterally to provide for easy access to the crank, and in order that this may be done we have shown the lower jaw 10 provided with a rib 10^b (see Fig. 2) which fits in a corresponding groove of the shank 15, so that by simply grasping the sign and the upper jaw 10 and turning the device laterally, the rib will ride up over the walls of its retaining groove and permit the desired turning movement, and after cranking the machine, the jaws and sign can be turned back when they will be held in the proper relation by the rib and its groove, the rib being held in place by the pressure of the spring 13.

It will be distinctly understood that the important thing in the invention is to provide a holding device which will secure the sign or card in the right position in relation to the vehicle and in such a way that the sign can be readily placed in position or removed.

The various details and accessories which we have shown are desirable to make the holder easy to operate and adjust, but these details can be changed considerably without in the least affecting the principle of the invention.

Having thus fully described our invention, we claim as new and desire to secure by Letters Patent:—

1. In a sign holder the combination of a clamp having overlapping flanges and having an extension, a shank pivotally connected to the extension, a post supported by the shank, a lower jaw loosely mounted on the post, means for holding the lower jaw against rotation, an upper jaw loosely mounted on the post, said jaws being provided with transverse grooves to receive the sign, and means for adjustably holding the upper jaw in engagement with the sign. 70

2. In a sign holder the combination of a clamp having overlapping flanges and having an extension, a shank adjustably connected to the extension and carrying a post adapted to hold the sign in a vertical position, a lower jaw supported by the post, an upper jaw slidably mounted on the post, said jaws being provided with transverse grooves to receive the sign, the posts terminating with an abutment, and a coil spring 85 interposed between the abutment and the upper jaw whereby the sign is held firmly by said jaws. 75

3. In a sign holder, the combination of an adjustable clamp having an extension, a shank vertically adjustably connected to the extension, the shank being provided with a groove in its upper side, a post supported by the shank at right angles thereto, a lower jaw loosely mounted on the post and having a tongue adapted to register with the groove in the shank, an upper jaw loosely mounted on the post, said jaws being provided with transversely extending grooves to receive the sign, a nut secured on the end of the post, and a spring encircling the post interposed between the nut and the upper jaw whereby the upper and lower edges of the sign are held firmly by said jaws. 90 95 100
